(57) **CLAIM**

The ornamental design for a “combined wet/dry vacuum cleaner,” as shown and described.

DESCRIPTION

FIG. 1 is a right side perspective view taken from the front and side showing my new design, and

FIG. 2 is a front elevation view thereof;

FIG. 3 is a left side elevational view, the right side elevational view being a mirror image thereof;

FIG. 4 is a top plan view thereof;

FIG. 5 is a rear elevational view thereof;

FIG. 6 is a front elevation view of the combined wet/dry vacuum cleaner with a handle that does not form part of the claimed invention;

FIG. 7 is a left side elevational view of the vacuum with the handle; and,

FIG. 8 is a rear elevation view of the vacuum with the handle.

The broken line showing of FIGS. 6-8 is for illustrative purposes only and forms no part of the claimed design.
